UNITED STATES PATENT OFFICE.

FRANK BRUDER, OF NEW YORK, N. Y.

COMBINATION CAP AND BONNET.

1,019,019.

Specification of Letters Patent.

Patented Mar. 5, 1912.

Application filed July 19, 1911. Serial No. 639,344.

To all whom it may concern:

Be it known that I, FRANK BRUDER, a citizen of the United States, and a resident of the city, county, and State of New York, 5 have invented a new and useful Improvement in Combination Caps and Bonnets, of which the following is a specification.

The object of my invention is to provide a cap, preferably made of fur, which may 10 be used either as a hat or cap on top of the head or as a hood, according to the wishes of the wearer, so that the cap is adaptable for either moderate or very cold weather, and is particularly useful for women riding 15 in automobiles. This object is accomplished by my invention, one embodiment of which is described below.

For a more particular description of my invention, reference is to be had to the accompanying drawings forming a part 20 hereof.

Figure 1 is perspective view of my improved hat. Fig. 2 is a rear elevation of the same. Fig. 3 is a sectional view taken on 25 the line 3-3 of Fig. 2 looking in the direction of the arrows. Fig. 4 is a view similar to Fig. 2, except that portions are broken away and more clearly reveal the structure. Fig. 5 is a perspective view of my improved 30 hat when converted into the shape needed for a hood. Fig. 6 is an end elevation of the structure shown in Fig. 5.

Throughout the various views of the drawings, similar reference characters designate 35 similar parts.

While I show a fur hat I in the drawings, it is to be understood that my invention is equally applicable to cloth or worsted hats or hoods, although it is preferable to use it 40 for fur hats, and so I will describe it in this embodiment.

The hat I comprises the crown 2 and a brim 3, the crown being preferably covered with some dark fur and the border with a 45 light gray or other fur, but this may be varied to suit the preference of the maker. The rear of the crown 2 is slotted at 4 and the ends of the brim 3 are curved as shown on 5 or in substantially this way, for a purpose 50 that will appear below. The walls of the slit 4 are reinforced by a suitable strip 6 as shown in Fig. 3, and by a lining 7, the strip 6 and lining 7 being inserted in a manner which will now be described.

The fur of the crown 2 is bent back upon 55 itself to form a hem at 8, which is secured

to the lining 7 by means of stitches 9. The lining 7 is bent about the reinforce 6 and continued until it is connected to a second lining 10 by suitable stitches 11, the lining 10 being folded over a buckram or similar stiffener 12 by which the hat I is secured on the wearer. Suitable rings 13 are secured by stitches 14 to the lining 7 and placed between the lining 7 and 10, two of these rings 15 being placed on each side and the ribbons 15 pass through these rings 13.

The reinforces 6 consist of two metal spring strips or similar strips 16 and 17 united at the top, by a suitable crossing 18 70 to which they are pivoted by pins 19 or other suitable means.

The ribbons 15 are passed through the rings 13 as shown in Fig. 4, that is, first through the top rings 13 then down on the 75 same side through the rings 13 and across to the opposite rings, and then down so that by drawing the ends of the ribbons 15, the slit 4 may be either opened or closed.

The device is used as a hat when in the 80 condition indicated in Figs. 1 and 2, and then the ribbons 15 may be passed about the neck of the wearer, whereby the hat is held in place. When the hat is used as a hood, the brim 3 is turned down into the 85 position indicated in Fig. 6. The ribbons 15 are then loosened as indicated in dotted lines and then the hood is applied to the head and neck of the wearer in the position in Fig. 5. By reversing this operation 90 the hood may be changed back to a hat and worn as before.

While I have shown and described one embodiment of my invention, it is obvious that it is not restricted thereto, but is broad 95 enough to cover all structures that come within the scope of the annexed claims.

What I claim is:—

1. In a device of the class described, a hat comprising a crown, a brim substantially 100 co-extensive with the crown and flexibly united to and adapted to be raised and lowered with respect to said crown, a slit formed in the crown, extending through the brim, and means for adjustably connecting 105 the edges of said slit.

2. In a device of the class described, a hat comprising a crown, a brim, a slotted portion, ribbons and means for holding said ribbons in said slotted portion. 110

3. In a device of the class described, a crown, a brim, a slotted portion, a lining,

reinforces, rings, and ribbons passing through said rings so that said hat may be worn either as a hat or a hood at the option of the wearer.

- 5 4. In a device of the class described, a crown, a brim, a slotted portion with a lining secured therein, reinforces on each side of said hood, rings means for uniting parts of one of said reinforces on each side of said hood, and a ribbon adapted to pass through

said rings, whereby said hood may be opened or closed at the option of the wearer.

Signed at the city of New York, county of New York and State of New York, this 18th day of July, 1911.

FRANK BRUDER.
